UNITED STATES PATENT OFFICE.

JOSEPH E. KENNEDY, OF NEW YORK, N. Y.

MEANS FOR DISCHARGING PULVERIZED MATERIAL FROM BINS, &c.

1,288,025.

Specification of Letters Patent.

Patented Dec. 17, 1918.

Application filed March 16, 1917. Serial No. 155,307.

To all whom it may concern:

Be it known that I, JOSEPH E. KENNEDY, a citizen of the United States, and a resident of the borough of Manhattan, city, county, and State of New York, have invented certain new and useful Improvements in Means for Discharging Pulverized Material from Bins, &c., of which the following is a specification.

- 10 The object of my invention is to insure an even, uniform feed, both as to quantity and pressure, of reduced or comminuted material from a storage bin or similar receptacle irrespective of the mass of material contained 15 in said holder. Difficulty has heretofore been experienced in controlling and counter-acting the pressure exerted by the material in a storage receptacle of this character, especially when the same is full, or approxi- 20 mately so, because under such conditions the excess of weight tends constantly to force the material through the exit much more rapidly than is desirable, whereas when the level of material in the bin is low, the pres- 25 sure will obviously be materially reduced, even possibly below that sufficient to effect a continuous flow in adequate quantity.

I obviate this difficulty by my invention which consists essentially in interposing be- 30 tween the exit and the bin a discharge chamber housing rotatable screw feed mechanism which receives the pulverized material from apertures in the floor of the bin and trans- 35 fers it to said exit,—the weight of material in the bin being sustained by the floor plate thereof, which also constitutes the top of the said discharge chamber, and the screw feed positively conveying the material to the exit at an even speed and uniform pres- 40 sure, all as hereinafter more fully set forth.

In the accompanying drawings,

Figure 1, is an elevation of the lower por- 45 tion of a bin or container for disintegrated material provided with my means for dis- charging the contents thereof;

Fig. 2, is a horizontal section taken upon plane of line 2—2, Fig. 1;

Fig. 3, is a horizontal section taken upon plane of line 3—3, Fig. 1;

50 Fig. 4, is a vertical section taken upon plane of line 4—4, Fig. 2.

The convergent lower side walls b , b , of the bin or similar receptacle B, for holding and dispensing pulverized material, cause 55 the descent of such material by gravity to the floor plate b' , which also constitutes the

top plate of the discharge feed chamber d , in which is situated the positive feed screw mechanism by which the pulverized material is conveyed from the apertures b^2 , b^2 , (Fig. 60 2) in said floor plate b' , to the exit e , in the bottom plate d' , of the discharge chamber d ,—said exit e , being provided with a spout or chute e' , by which the discharged material may be delivered to auxiliary apparatus of various kinds and for various pur- 65 poses.

The positive screw feed mechanism consists preferably of two parallel screw conveyers c , c , of like pitch and inclination. 70 These extend on either side of the exit e , and convey the pulverized material which descends through the apertures b^2 , in the plate b' , in opposite directions to said exit e . If the latter becomes clogged for any reason 75 the screw conveyers c , c , simply cause the material in the discharge chamber d , to circulate from one end thereof to the other, back and forth, until the obstruction abates,—the feed to the exit e , thus being 80 continuous regardless of the condition of the latter, and the screw conveyers c , c , tak- 85 ing no more from the bin apertures b^2 , b^2 , than they can dispose of. Furthermore this provision for circulation of material within 90 the discharge chamber d , relieves the pressure and prevents the crowding and forcing of material through the exit e , when not disposed of promptly by the auxiliary apparatus. 90

The bin apertures b^2 , b^2 , are of a combined area aggregating approximately that of the exit e , so that the floor plate b' , which may be designated the pressure relief plate, sus- 95 tains the major part of the weight of the mass of comminuted material in the recep- 100 tacle B, thereby obviating undue compact- ness and congestion, and affording the least possible degree of resistance to the opera- tion of the conveyers c , c , and permitting them to feed the material to the exit e , in relatively loose, uniform condition, which is a pre-requisite for effective service in the auxiliary apparatus.

The bin apertures b^2 , b^2 , are by prefer- 105 ence out of coincidence with the exit e , so that there is no possibility of the contents of the bin exercising direct pressure on the material ejected through said exit e .

The screw conveyers may be mounted and 110 rotated in opposite directions by any suitable means. By way of illustration in the

drawings they are connected by intermeshing gears g , g , and driven by a pulley p .

It is to be noted that by my method of effecting the discharge of the comminuted material the latter is withdrawn from the bin only as required, and that while the feed to the exit c , is positive in the sense that material is always presented thereto, still it is not absolutely imperative in that undue resistance to exit will be automatically met and remedied by the continuous circulation of the material in the discharge chamber d , by means of the screw conveyers c , c . Furthermore, there can be no flooding of the material into the discharge chamber, nor passage therethrough faster or slower than at the speed and quantity prescribed by the screw conveyers c , c , so that a definite amount of material is abstracted from the hopper and ejected from the discharge chamber at an even speed, which is an important factor in various arts in which my system of delivering comminuted material may be employed.

I have herein shown and described my discharge chamber d , as situated immediately below the pressure relief floor plate

b' , of the bin, although I do not limit myself thereto, since communication between the lower part of the bin and said discharge chamber d , is the essential feature in this respect, in conjunction with the interposition of a pressure relief plate through which such communication is effected.

What I claim as my invention and desire to secure by Letters Patent is,

Means for discharging pulverized material from bins, comprising a floor therefor consisting of a pressure relief plate formed with openings, a discharge chamber underneath said relief plate formed with a discharge spout misregistering or out of coincidence with the said openings in the relief plate above, parallel screw conveyers threaded in the same direction positioned in said discharge chamber, and means for rotating said screw conveyers in opposite directions, whereby a circulation of material in the discharge chamber is effected, for the purpose described.

JOSEPH E. KENNEDY.
